[57] CLAIM

The ornamental design for a computer disc with transparent window for slip-in label, as shown and described.

DESCRIPTION

FIG. 1 is a top, side, perspective view of a computer disc with transparent window for slip-in label showing my new design, the label being inserted;

FIG. 2 is a top, side, perspective view thereof wherein the label is partially inserted;

FIG. 3 is an enlarged fragmentary end view thereof as seen in the direction of line 3-3 of FIG. 1;

FIG. 4 is an enlarged fragmentary sectional view thereof taken along line 4-4 of FIG. 2;

FIG. 5 is a reduced top plan view thereof wherein the label is inserted;

FIG. 6 is a reduced bottom plan view thereof;

FIG. 7 is a reduced top plan view thereof wherein the transparent window is removed and the label is inserted therein;

FIGS. 8, 9, 10 and 11 are respectively reduced rear, front, right and left side elevational views thereof.

The label is shown in broken lines in FIGS. 1, 2, 5 and 7 for illustrative purposes only and forms no part of the claimed design.
